UNITED STATES PATENT OFFICE.

JOSEPH KURCZEWSKI, OF DETROIT, MICHIGAN.

GAUGE.

Application filed May 29, 1923. Serial No. 642,250.

To all whom it may concern:

Be it known that I, JOSEPH KURCZEWSKI, a citizen of the United States of America, residing at Detroit, in the county of Wayne, 5 and State of Michigan, have invented certain new and useful Improvements in Gauges, of which the following is a specification.

This invention relates to certain new and 10 useful improvements in gauges and particularly to the type employed by carpenters in marking window frames to indicate the point at which openings are to be made for supporting sash cord pulleys.

15 The primary object of the invention resides in the provision of a gauge of the above type wherein the marking devices carried by the gauge frame are arranged in pairs and adjustably mounted in the gauge frame 20 to permit the marking of a window frame at the desired point for the boring of sash cord pulley openings.

With the above and other objects in view as the nature of the invention is better 25 understood, the same consists of the novel form, combination and arrangement of parts hereinafter more fully described, shown in the accompanying drawing and claimed.

In the drawing, wherein like reference 30 characters designate corresponding parts throughout the several views,

Figure 1 is a front elevational view of a 35 gauge constructed in accordance with the present invention showing the spaced marking devices adjustably mounted in the gauge frame,

Figure 2 is a side edge elevational view showing the gauge operatively positioned upon a window frame that is illustrated 40 by dotted lines,

Figure 3 is a rear elevational view of the device,

Figure 4 is a cross-sectional view taken on line IV—IV of Fig. 1 showing a guide 45 parting strip carried by the gauge frame, and showing by dotted lines, the guide parting strip removed when the gauge is employed on a window frame having the parting strip in position, and further showing 50 the clamping screws for the marking devices.

Figure 5 is a perspective view of the adjustable gauge block,

Figure 6 is a perspective view of the retaining strip for the marking spurs, and

Figure 7 is a perspective view of one of the spurs.

Referring more in detail to the accompanying drawing, the gauge embodies a frame including a block 1 having a flat 60 inner face 2 with the upper and lower ends of the outer face arched as at 3. The inner face 2 of the gauge frame is provided with a central longitudinal groove 4 into which a removable parting strip section 5 is positioned as illustrated in Fig. 4, the strip 5 extending the entire length of the block frame 1. A stop plate 6 is secured to the upper end of the frame 1 and overhangs the inner face 2 of the frame as at 6^a, the 65 stop plate being adapted to have the projecting edge 6^a thereof engage the upper end of a window frame F as shown in Fig. 2 for properly positioning the gauge upon a window frame during the marking thereof. 70 The window frame F has a groove G formed therein that receives the removable parting strip 5 for positioning the gauge upon the window frame, and in the instance where the parting strip is fixed to the frame F, 75 the removable parting strip 5 is removed from the gauge frame groove 4 for reception of the parting strip in the groove 4.

The inner face 2 of the gauge frame is provided with a pair of longitudinally extending pockets 7, one arranged at each side of the groove 4 and transversely alined as shown in Fig. 1, slotted openings 8 being formed in the outer face of the gauge frame in communication with the pockets 7, while the side walls of the gauge frame are longitudinally slotted as at 9, a face plate 8^a being secured to the outer face of the frame while a face plate 9^a is secured to the side edge thereof as shown in Figs. 2 and 3. 85

A gauge block 10 is adjustably mounted in each pocket 7, the block 10 being provided with a longitudinally extending groove 11 opening at the ends thereof and having a face plate 12 secured to the lower or inner side, and a face plate 13 secured to one side of the block, an opening being provided through the face plate 13 and adjacent wall of the block 10 as shown in Figs. 4 and 5. 90

A plurality of marking spurs are positioned in the groove 11 of the marking block, each spur including a marking point 14 and an angle base portion 15. The spurs are positioned in the grooves 11 with the angle portions 15 flatly engaging the bottom 105 110

wall of the groove as shown in Fig. 4 with the retaining strip 16 shown in Figs. 4 and 6 positioned in the groove above the angle base 15 and laterally of the marking points 5 14, the opposite ends of the strip 16 being angularly bent in opposite directions as at 17 to prevent longitudinal shifting movements thereof within the groove 11 of the block.

- 10 Set screws 18 pass through the side openings in the block 10 and engage the retaining strip 16 as shown in Fig. 4, to move the same into binding engagement with the spurs 14, the series of spurs in each block 15 groove 11 being anchored therein against movement. The longitudinal adjustment of the block members 10 is accomplished by the set screws 19 that extend through the grooves 8 of the gauge frame and engage at 20 their inner ends the lower faces of the gauge blocks 10, the set screws 19 being threaded into the gauge blocks for moving the same into engagement with the bottom walls of the pockets 7 to frictionally retain the block 25 against longitudinally shifting movement, such shifting movement of the block being accomplished by loosening the set screws 18 and 19, the block being shifted in the pocket 7 while the set screws move through the 30 slotted openings 8 and 9. With the gauge blocks properly positioned in the pockets 7, and the gauge frame mounted upon the window frame F, pressure on the gauge frame as by striking the face plate 8^a with a hammer 35 or other implement will cause the pointed spurs 14 to mark the surface of the window frame F to indicate the point at which openings are to be made for mounting the sash cord pulleys.
- 40 While there is herein shown and described the preferred embodiment of the present invention, it is nevertheless to be understood that minor changes may be made therein without departing from the spirit and scope 45 of the invention as claimed.

What is claimed as new is:—

1. In a gauge of the type described, a frame block having spaced pockets therein, a gauge block adjustably mounted in each 50 pocket, each gauge block having a longitudinal groove in the exposed side thereof, marking spurs removably mounted in the block groove, a retaining strip for the spurs and means for clamping the spurs and retaining strip in the block groove.

2. In a gauge of the type described, a frame block having spaced pockets therein, a gauge block adjustably mounted in each 55 pocket, each gauge block having a longitudinal groove in the exposed side thereof, marking spurs removably mounted in the

block groove, a retaining strip for the spurs, means for clamping the spurs and retaining strip in the block groove, and a top plate secured to the upper edge of the frame block and overhanging the working face thereof.

3. In a gauge of the type described, a frame block, a pair of gauge blocks adjustably supported on the frame block, a plurality of spur markers carried by each gauge block, a top plate secured to the upper edge of the frame block and overhanging the working face thereof, a retainer strip for the spurs, and angle base flanges carried by 75 the spurs disposed beneath the retaining strip.

4. In a gauge of the type described, a frame block having spaced pockets therein, a gauge block adjustably mounted in each pocket, each gauge block having a longitudinal groove in the exposed side thereof, marking spurs removably mounted in the block groove, a retaining strip for the spurs, means for clamping the spurs and retaining strip in the block groove, a top plate secured to the upper edge of the frame block and overhanging the working face thereof, and angle base flanges carried by the spurs disposed beneath the retaining strip.

5. In a gauge of the type described, a frame block, a pair of gauge blocks adjustably supported on the frame block, a plurality of spur markers carried by each gauge block, a top plate secured to the upper edge of the frame block and overhanging the working face thereof, a retaining strip for the spurs, angle base flanges carried by the spurs disposed beneath the retaining strip, and said frame block having a longitudinal groove in the working face for the reception of a removable parting strip.

6. In a gauge of the type described, a frame block having spaced pockets therein, a gauge block adjustably mounted in each pocket, each gauge block having a longitudinal groove in the exposed side thereof, marking spurs removably mounted in the block groove, a retaining strip for the spurs, means for clamping the spurs and retaining strip in the block groove, a top plate secured to the upper edge of the frame block and overhanging the working face thereof, angle base flanges carried by the spurs disposed beneath the retaining strip, and said frame block having a longitudinal groove in the working face for the reception of a removable parting strip.

In testimony whereof I affix my signature.

JOSEPH KURCZEWSKI.
